DRY SHAVER

Reinhard Willem Jacob Veersema, Eindhoven, Netherlands, assignor to North American Philips Co., Inc.

Application November 12, 1957, Serial No. 48,418

Term of patent 14 years

(Cl. D22—3)

FIG. 1.

FIG. 2.

FIG. 3.

FIG. 4.

Fig. 1 is a side perspective view of a dry shaver, showing my new design;

Fig. 2 is a front elevational view thereof, the back being plain and unornamented;

Fig. 3 is a side elevational view, the side opposite thereof being substantially similar in appearance; and

Fig. 4 is a top plan view thereof.

I claim:

The ornamental design for a dry shaver, as shown and described.
